UNITED STATES PATENT OFFICE.

FRED MACEY, OF GRAND RAPIDS, MICHIGAN.

FILE-BOX.

SPECIFICATION forming part of Letters Patent No. 634,061, dated October 3, 1899.

Application filed January 16, 1899. Serial No. 702,256. (No model.)

To all whom it may concern:

Be it known that I, FRED MACEY, a citizen of the United States, residing at Grand Rapids, in the county of Kent and State of Michigan, have invented certain new and useful Improvements in File-Boxes; and I do hereby declare the following to be a full, clear, and exact description of the invention, such as will enable others skilled in the art to which it appertains to make and use the same.

My invention relates to improvements in boxes for file-cases; and its object is to provide the box with a suitable drop-front, whereby the contents are readily accessible without removing the box from the case, and to provide the device with certain new and useful features hereinafter more fully described, and particularly pointed out in the claims, reference being had to the accompanying drawings, in which—

Figure 1 is a perspective of a device embodying my invention, and Fig. 2 a vertical section of the same through two of the boxes shown at the left of Fig. 1.

Like letters refer to like parts in both of the figures.

A represents any suitable case having rectangular compartments to receive the boxes and open at the front.

B represents the main portion of the box, which portion has a bottom, top, sides, and rear end, all permanently attached to each other, the bottom being longer than the top and of less length than the depth of the compartment in the case A, and the sides have inclined front edges extending from the front edge of the bottom to the same of the top.

Beneath the bottom of the box B and attached thereto is a subbottom consisting of two parts B' and B'', the latter of which extends beyond the bottom of the box B and to the full depth of the compartment in the case A. This subbottom is provided with a hinge D near the front of the bottom of the box B and beneath the same, and its forward portion B'' turns freely on this hinge. To this front portion B'' is attached a suitable panel E, adapted to close the front opening of the compartment in the case A. Connecting the sides of the panel and the hinged portion B'' of the subbottom are triangular sides C, hav-

ing inclined rear edges and arranged outside the planes of the sides of the box B.

F is a suitable pull or handle whereby the box may be drawn out of the compartment in the case A.

The subbottom B', together with the front portion B'' thereof, forms a continuous plane surface for the box and slides freely on the bottom of the compartment in the case, the portion B'' being below the plane of the bottom of the box B and the sides C being outside the sides of said box, the hinged front portion of the box formed by the front portion B'' of the bottom, the sides C and the panel E will close freely over the ends of the papers in the box B and be properly held in place in the compartment and close the same when fully run back into said compartment. When the box is drawn out of the compartment to a point beyond the hinge D, this front will swing downward wholly below the front end of the box B, thus fully exposing the ends of all of the papers contained in the box.

Having thus fully described my invention, what I claim, and wish to secure by Letters Patent, is—

1. In a file-case, the combination with a supporting-casing of a drawer movable horizontally therein, a supplemental bottom for said drawer extending over the whole of the true bottom and projecting beyond the outer end of the latter, and a front consisting of two parts united at their edges at a right angle one to the other, an edge of one of said parts being hinged to the outer edge of the true bottom of the drawer beneath the projecting portion of the supplemental bottom.

2. The combination of a substantially rectangular box having an open front end, a subbottom beneath the bottom of the box and immovably attached thereto and also having a hinge beneath the forward part of the box, a panel and sides attached to the subbottom, said sides overlapping the sides of the box and on the outside thereof, substantially as described.

3. A file-box consisting of a box having an open and inclined front end, the top being shorter than the bottom, a subbottom extending beneath and beyond the bottom of the

box and provided with a hinge beneath the front of the box, a front panel attached to said subbottom, and triangular sides connecting the panel and forward portion of the 5 subbottom and overlapping the sides of the box at the lower angle of the forward end and on the outside thereof, substantially as described.

4. The combination of a case having rectangular compartments, boxes having open inclined front ends, subbottoms extending beneath said boxes and beyond the same and having hinges beneath the front part of the

boxes, panels attached to the subbottoms at the front and closing the openings in the case, 15 and triangular sides connecting the panels and subbottoms and overlapping the boxes on the outside of their lower front portions, substantially as described.

In testimony whereof I affix my signature 20 in presence of two witnesses.

FRED MACEY.
